UNITED STATES PATENT OFFICE.

WILLIAM B. HALE AND ROBERT E. DURINGER, OF FORT WORTH, TEXAS;
SAID HALE ASSIGNOR TO BENJAMIN C. EVANS, OF SAME PLACE.

SPARK-ARRESTER FOR SMOKE-PIPES.

SPECIFICATION forming part of Letters Patent No. 448,918, dated March 24, 1891.

Application filed November 24, 1890. Serial No. 372,448. (No model.)

To all whom it may concern:

Be it known that we, WILLIAM B. HALE and ROBERT E. DURINGER, citizens of the United States, residing at Fort Worth, in the county 5 of Tarrant and State of Texas, have invented certain new and useful Improvements in Spark-Arresters for Smoke-Pipes; and we do hereby declare the following to be a full, clear, and exact description of the invention, such 10 as will enable others skilled in the art to which it appertains to make and use the same.

Our invention relates to smoke-stacks for steam-boilers, and is more especially applicable to boilers for thrashing-machines, saw-mills, locomotives, or other portable boilers, where for convenience in transportation a short smoke-stack must be used, and where at 15 the same time there is either great danger to the surrounding property from sparks or great annoyance to the passengers from flying cinders.

In the drawings, where the same parts are indicated by the same letters, we show our invention as applied to a boiler similar to 20 those used in either railway-locomotives or in portable thrashing-machines.

Figure 1 represents a side view of the said boiler, part of the smoke-pipe being broken away to better illustrate our invention. Fig. 30 2 represents an end view of the boiler, with our attachments as seen from the end opposite the furnace.

A represents the boiler. The furnace, flues, &c., not being peculiar to our invention, are 35 not shown.

B represents the smoke-stack, having one complete turn, as shown in both figures.

C represents a coarse wire screen secured in the lower portion of the curve of the smoke-pipe, and tilted, as shown. The upper end of 40 C should preferably overhang the lowest part of the curve in the smoke-stack, and at this lowest part we place a cinder-pipe D. Said pipe has preferably a conical bouching d for the better entrance of the cinders, and to prevent choking of the said pipe we have a steam-jet E, controlled by the valve e. Some arrangement may also be made for turning this valve from the rear of the boiler. The smoke-stack itself may also have a steam-jet or other 45 means for forcing the draft; but as this is not

peculiar to our invention it has not been shown in the drawings.

Beneath the pipe D we have a pan G, secured either to the boiler, lagging, or frame-work in any convenient way. This pan G has a bottom H, hinged at one side h, and held up at the other h' by the chain K, which passes over a roller k', attached to any convenient part of the boiler, lagging, or frame-work, the 5 said chain leading to the rear of the boiler, where it is secured. k represents any convenient hand attachment for raising and lowering the bottom H. After the products of combustion enter the smoke-stack they are 65 carried through the curved portion, where the solid particles naturally fall to the bottom. The wire screen C also serves as a further check to the solid particles, and from its overhanging position the said particles striking 70 it are thrown downward and fall into the pipe D. Should the pipe D become clogged in any way and the cinders gather in the bottom of the curve of the smoke-stack, the steam-jet E is turned on. Before doing this it would 75 be advisable to lower H by slackening off the chain K; but no accident would occur should this be omitted, as H cannot be made to fit very closely, and moreover would yield sufficiently to allow the steam to escape above its 80 edges. Whenever it is desired to empty the pan G, the chain K may be slackened off and the bottom H allowed to drop enough to allow the cinders to fall out. By this means not only are sparks arrested, but the cinders from 85 the smoke-pipe are gathered into a receptacle from which they may be easily taken for the various uses to which they are put.

Having now described our invention, what we claim, and desire to secure by Letters Patent, is—

1. In attachments for steam-boilers, the combination of a bent smoke-pipe having one complete turn downward, a cinder-pipe opening into the lowest portion of said turn, and 95 a steam-jet actuated by hand for blowing down said cinder-pipe, substantially as described.

2. In attachments for steam-boilers, the combination of a bent smoke-pipe having one 100 complete turn downward, a cinder-pipe opening into the lowest portion of said turn, and

a steam-jet actuated by hand for blowing down said cinder-pipe, a receptacle beneath said cinder-pipe for the cinders, said receptacle having a hinged door for dumping the said cinders, substantially as described.

3. In attachments for steam-boilers, the combination of a bent smoke-pipe having one complete turn downward, a cinder-pipe opening into the lowest portion of said turn, a coarse wire screen tilted backward and overhanging said pipe, and a steam-jet actuated by hand for blowing down said cinder-pipe, a receptacle beneath said cinder-pipe for the cinders, said receptacle having a slanting bottom hinged at the upper end and secured at the lower end by means of a chain passing over a suitable roller and leading to the rear of the boiler, substantially as and for the purposes described.

4. In attachments for steam-boilers, the combination of a bent smoke-pipe having one complete turn downward, a cinder-pipe opening into the lowest portion of said turn, and a coarse wire screen tilted backward and overhanging said turn, a receptacle having a slanting bottom hinged at the upper end and secured at the lower end by means of a chain passing over a suitable roller and leading to the rear of the boiler, substantially as and for the purposes described.

In testimony whereof we affix our signatures in presence of two witnesses.

WM. B. HALE.
ROBT. E. DURINGER.
